(57) **CLAIM**

The ornamental design for a shopping basket, as shown and described.

DESCRIPTION

FIG. 1 is a front perspective view of a shopping basket with the carry handle in the stored position and the extendable handle in the stored position;

FIG. 2 is a front view thereof,

FIG. 3 is a right side view thereof, the left side view thereof being a mirror image of the right side view,

FIG. 4 is a top view thereof,

FIG. 5 is a rear view thereof,

FIG. 6 is a bottom view thereof; and,

FIG. 7 is a rear perspective view thereof with the extendable handle in the extended position.

The broken lines are included for the purpose of illustrating portions of the article and form no part of the claimed design.

It is certified that error appears in the above-identified patent and that said Letters Patent is hereby corrected as shown below:

On the Title Page, item (75) should read as follows:

Item (75) Inventors: Isabel Gimeno, Zaragoza (ES);
Manuel Rodriguez, Zaragoza (ES);
Jose Antonio Puertolas, Zaragoza (ES)

On the Title Page, item (73) should read as follows:

Item (73) Assignee: Araven S.L., Zaragoza (ES)

The following are added to the Title Page in the left column:

Item --(30) Foreign Application Priority Data

Nov. 18, 2004 (ES) P200402780
Oct. 8, 2007 (EP) 803887-0001
Oct. 8, 2007 (EP) 803887-0002
Oct. 8, 2007 (EP) 803887-0003
Oct. 8, 2007 (EP) 803887-0004--

Signed and Sealed this
Twenty-third Day of August, 2011

David J. Kappos
Director of the United States Patent and Trademark Office
